UNITED STATES PATENT OFFICE

JAMES E. FITZGERALD, OF YOUNGSTOWN, OHIO, ASSIGNOR TO THE NILES STEEL PRODUCTS COMPANY, OF NILES, OHIO, A CORPORATION OF OHIO

SHEET METAL CONTAINER

Application filed August 19, 1926. Serial No. 130,215.

This invention relates to an improved sheet metal container and to the method of securing the head thereto. The present container is of the type wherein the head is secured by means of a sealing ring which is adapted to be secured in place by crimping inwardly at intervals a continuous flange of the ring, the latter having its ends secured together by spot welding or otherwise so that they can be separated or broken apart and permit the ring to be stripped off the container head.

The invention may be briefly summarized as consisting in certain novel features of construction and steps of the improved method which will be described in the specification and set forth in the appended claims.

In the accompanying sheets of the drawings wherein I have illustrated the preferred form of the invention, Fig. 1 is a side view of the container. Fig. 2 is a fragmentary perspective view showing how the ends of the sealing ring overlap and are fastened in a manner such that the ring can be separated at this point. Fig. 3 is a sectional view showing the top portion of the container and illustrating a closing tool which may be utilized in fastening the head of the container. Fig. 4 is a perspective view of a portion of the upper part of the container. Fig. 5 is an enlarged, detail sectional view showing how the top of the container body, the head and the sealing ring are arranged prior to the closing operation. Fig. 6 is a sectional view substantially along the line 6—6 of Fig. 4 after the head is secured in place by crimping inwardly at intervals the continuous flange of the sealing ring. Fig. 7 is a similar view substantially along the lines 7—7 of Fig. 4, showing the action of one of the jaws of the closing tool.

The body portion 10 of the container is preferably provided near the top with an outstanding annular rib 12, the outside diameter of which is preferably slightly greater than the diameter of the body 10, and above the rib 12 being tapered inwardly so as to form a reduced neck portion, and at the extreme top being provided with a rolled bead 13 the out-

side diameter of which is somewhat less than the diameter of the body 10.

The head 14 of the container has a depressed portion which is adapted to fit rather closely on the inside of the bead 13 and it has an outstanding flange 15 which projects over the bead 13 and over a suitable gasket 16 which is adapted to be tightly compressed in the closing operation between the flange 15 and the bead 13.

The head 14 is secured in place by means of a sealing ring 17 provided with an inwardly extending flange 18 which is adapted to overlie the flange 15 of the head and with a downwardly extending flange 19 which, when the sealing ring and head are pressed downward in the sealing operation, extends down some distance below the bead 13. The sealing ring 17 is continuous, the ends being fastened together in a manner such as to form a normally secure but severable joint, and this is preferably done by overlapping the ends as indicated at 20 and spot welding them together or otherwise fastening them together.

It is a feature of the present invention, that in the closing operation after the head and sealing ring are pressed downward tightly compressing the gasket, the continuous outer flange 19 of the sealing ring is crimped in at intervals at which time equally spaced portions 21 of the flange 19 are bent inwardly beneath the bead 13 into engagement with and at substantially right angles to the reduced neck portion of the body 10 immediately beneath the bead thus adding greatly to the strength of the top portion of the pail. This leaves between the inwardly crimped or bent portions 21 uncrimped portions 22 which in the crimping operation are drawn inwardly somewhat toward or against the reduced neck 90 of the body 10, as illustrated in Fig. 6, and are curved or bowed, thus reinforcing the sealing ring and adding to the holding action of the crimped portions as there is formed the equivalent of curved trusses joining the crimped 95 portions.

The crimping operation is preferably accomplished by a closing tool illustrated in Figs. 3 and 7, this closing tool including an annular plate 23 which engages the flat de- 100

pressed part of the head and has its marginal portion recessed to fit closely over the in-turned flange of the sealing ring. Pivotally connected to the margin of the plate 23 are levers 24 having at their lower ends short closing jaws 25, the upper ends of the levers being connected by adjustable links 26 to a sleeve 27 slidable upon a vertical guide 28 projecting up from the center of the plate, the sleeve having a suitable handle 29 adapted to be grasped by the operator. The lower part of the guide 28 may be surrounded by a spring 30 to cushion the downward stroke of the sleeve and to elevate it after the closing stroke.

In operation, the closing tool is placed down on the head and sealing ring after the latter are properly positioned at the top of the container, and then with one downward stroke the jaws 25 are simultaneously moved inward, the head and sealing ring being at the same time pressed downward so as to compress the gasket, as previously explained. By this operation uniformly spaced portions of the continuous flange of the sealing ring are bent inwardly at intervals and brought up tightly against the under side of the bead, this operation leaving, as previously explained, the intervening uncrimped portions which are, however, drawn or curved inwardly, as explained.

In this manner the head is fastened in place very securely and a very strong construction is provided at the top of the container due in a large measure to the form of the sealing ring and to the fact that the sealing ring has a continuous flange which is crimped at intervals only, leaving the downwardly extending but inwardly curved uncrimped portions which are protected against catching on an object and being pulled downwardly not only by reason of the outstanding rib 15 but because the edges or marginal portions thereof are curved inwardly toward the container body, the curving or bowing serving also to strengthen the construction of the closed pail and to add to the holding action of the crimped portions as explained above.

To remove the head it is only necessary to insert a suitable tool beneath the sealing ring where the joint 20 occurs and pry the ends apart. To facilitate this operation, the flange of the ring may be provided adjacent the joint with a short, upstanding pocket 20a to receive the end of the tool. When the joint has been loosened, the ring can be readily stripped off.

Having described my invention, what I claim as new is:

1. A container comprising a body having a bead at the top, a head having a portion extending over the bead, and a sealing ring for securely fastening and sealing the cover having a flange extending inwardly over said portion of the head and having a continuous

downward flange crimped inward at intervals beneath said bead leaving intervening uncrimped portions.

2. A container having at the top an annular shoulder, a head fitted to the container and having a marginal flange projecting over the shoulder, and a sealing ring for securely fastening and sealing the cover having a flange projecting inwardly over the flange of the head, and having a continuous downwardly projecting flange bent inwardly at intervals at substantially right angles to said flange beneath the shoulder leaving intervening uncrimped portions.

3. A container having a bead at the top, a head fitted to the container and having an outwardly extending marginal flange projecting over said bead, and a sealing ring for securely fastening and sealing the head having a flange projecting inwardly over the flange of the head, and having a continuous downwardly projecting flange having portions bent inwardly at intervals at substantially a right angle to said downwardly projecting flange beneath the bead leaving intervening uncrimped portions having curved connections with the inwardly bent portions.

4. A sheet metal container comprising a body having a closed hollow bead at the top, closing and sealing means therefor including a cover extending over said bead, and including a continuous downwardly extending flange surrounding the bead and crimped inwardly at intervals against the underside of the bead, leaving intervening uncrimped portions.

5. A sheet metal container comprising a body having a closed hollow bead at the top, closing and sealing means therefor including a cover extending over said bead, and including a continuous downwardly projecting flange having portions bent inwardly at intervals at substantially a right angle to said downwardly projecting flange against the underside of the bead, leaving intervening uncrimped portions.

In testimony whereof, I hereunto affix my signature.

JAMES E. FITZGERALD.
